DETERGENT AID

Louis A. Mikeska, Westfield, N. J., assignor to
Standard Oil Development Company, a corpora-
tion of Delaware

No Drawing. Application January 29, 1938,
Serial No. 187,662

16 Claims. (Cl. 260—512)

This invention relates to improved detergent aids, more particularly to poly-alkyl phenol derivatives of strong poly-basic mineral acids in which at least two of the alkyl groups contain more than four carbon atoms each, and preferably between about 5 and 8 carbon atoms each.

It has already been proposed to prepare wetting agents and detergents by reaction of olefines, phenol, and sulfuric acid. The products obtained by such reactions contain a mixture of mono- and di-alkyl phenol derivatives, even when the olefines are used substantially in excess of the phenols. These sulfonates are not distillable, and the separation of the product into the separate mono-alkylated and di- or poly-alkylated components is extremely difficult, usually a practical impossibility.

It has now been found that detergent aids of greatly increased effectiveness are obtained if the poly-alkyl phenol sulfonates are prepared substantially free of mono-alkyl phenol sulfonates. This is especially true with alkyl derivatives in which the alkyl groups contain from 5 to about 8 carbon atoms, preferably 5 or 6 carbon atoms.

One suitable method for preparing the improved detergent aids of this invention is to react the corresponding poly-alkyl phenol with a strong poly-basic mineral acid, preferably a sulfonating agent, such as strong or fuming sulfuric acid, chloro-sulfonic acid, and the like. The resulting mineral acid derivatives may be used as obtained for uses in which acid detergent aids are desired. They may also be neutralized with suitable bases, such as the alkali metal bases and nitrogen bases, such as ammonia and the amines, and the resulting salts have been found to be especially active wetting agents. These salts have surprising characteristics in that their wetting ability is substantially greater in both hard water and in acid solutions than in neutral aqueous solutions.

It has also been found that such reaction products contain fractions which are separable by extraction with ether; the ether soluble fraction being an even more effective wetting agent than the total salt, and the ether insoluble fraction being a very poor wetting agent.

The following example is presented as illustrative of this invention and describes one suitable method for the preparation of the improved detergent aids described herein:

Example I

55. 50 grams of di-amyl (1,3) phenol was placed in a one liter, three-way flask, fitted with a mechanical stirrer and mercury seal, drop funnel and gas inlet tube, and thermometer and gas outlet tube and was cooled therein to 10° C. 60 26 grams of chlorosulfonic acid were then added

dropwise while stirring and cooling to keep the reaction temperature between 50 and 60° F. during a period of 40 minutes. After adding all the acid, the cooling bath was removed and the reaction mixture was allowed to warm up to room temperature, air being blown through the reaction mixture for about 3 hours. The mixture was then neutralized with aqueous sodium hydroxide. Isopropyl alcohol equal to half the volume of the resulting mixture was added. This was followed by the addition of naphtha and thorough shaking. The mixture was then permitted to settle into a lower water-alcohol layer containing the desired product and an upper naphtha layer containing the unreacted materials. The aqueous solution was drawn off and was extracted several times with naphtha to remove additional unreacted materials. The aqueous solution was then dried on a steam bath and there was obtained 63.1 grams of a light colored, solid product representing a yield of more than 90% of the theoretical.

58 grams of this crude product were extracted with ethyl ether and the ether extract was evaporated to dryness. 77.3% of the total product was obtained as the ether extract.

The characteristics of these products as wetting agents were determined by the method of Draves and Clarkson, Proc. Am. Assoc. Textile Chem. Colorists 1931, 109. The wetting numbers of the crude product and of the ether extract and residue were obtained with solutions containing 0.2% of the product in distilled water, in hard water containing 300 parts per million of calcium, and in an aqueous solution containing 0.3% of sulfuric acid. The wetting numbers and appearance of these solutions are indicated in the following table:

WETTING NUMBERS—SECONDS
Solution—0.2% of wetting agent

Wetting agent	Water	Hard water	Acid	Appearance of solution
Crude product	28	9	12	Clear solution, faint straw color.
Ether extract	11	3	4	Slightly opalescent. Clear solution. Clear solution, faint straw color. Opalescent.
Ether insoluble	Above 600			Clear. Clear.

Other poly-alkyl phenols suitable for use in preparing the improved detergent aids of this invention by the process described in the above example are those containing 5 to 8 or more carbon atoms in each alkyl group. The alkyl groups may be normal, iso, secondary, or tertiary, or even cyclic. Aryl derivatives of alkyl radicals are also contemplated, such as benzyl, tolyl, 55

60 65

cresyl, phenyl, and the like. The poly-alkyl phenols may be obtained by alkylating a phenol with suitable alkylating agents, such as alcohols, olefines, alkyl sulfates and alkyl halides, of 6 to 8 or more carbon atoms per molecule. The alkylated phenols prepared from such olefines, or their corresponding alcohol, sulfate, or halide derivatives, contain branched carbon chains in the alkyl group, the carbon atom attached to the aromatic ring being also connected to two or three other carbon atoms of the alkyl group. These branched alkyl phenols and particularly the tertiary di-alkyl phenols, are preferred for this invention. The olefines may be obtained by cracking petroleum products and cracked fractions of suitable boiling range may be used directly for the alkylation. Such fractions may be of relatively wide boiling range containing olefines of different molecular weights such as the pentenes and hexenes, or narrower cut fractions containing only isomeric olefines of the same molecular weight such as the pentenes, may be used. The olefines may also be polymers of low molecular weight olefines, such as dimers, trimers, tetramers, etc., of olefines of preferably less than 5 carbon atoms per molecule, particularly of isobutylene.

The alkyl phenols may be prepared by any suitable method such as the methods described in U. S. Patents Nos. 1,954,985 and 2,045,749 using preferably a large proportion of olefines to phenols. The products obtained by such methods will contain mixtures of mono-, di-, and possibly higher poly-alkyl phenols. These products should be separated by suitable methods, such as distillation, to remove the mono-alkyl phenols from the higher poly-alkylated phenols, the latter then being used for the production of the improved detergent aids of this invention. It is generally preferable in such cases to use a substantially pure di-alkyl phenol fraction, although mixtures of di- and higher poly-alkyl phenols may also be used.

While phenol is preferred in this invention, derivatives thereof may also be used. Examples of these are cresol and other alkyl phenols, poly-hydroxy phenols such as resorcinol, hydro-quinone and the like, thio-phenols, or under some circumstances, crude commercial products containing substantial quantities of phenol or cresol, such as the crude phenol or cresol fractions obtained as coal-tar distillate fractions; the petroleum phenols such as the phenolic compounds extracted from petroleum crudes and distillate fractions thereof by alcoholic alkali; also mono- and poly-hydroxy derivatives of poly-nuclei hydrocarbons, such as alpha and beta naphthol or aryl substituted phenols. The petroleum phenols mentioned above are preferably obtained from kerosene and gas oil distillates. They may be extracted with alcoholic sodium hydroxide. The extract will contain oil and some naphthenic acids, if such are present in the oil being extracted. Dissolved hydrocarbon oil may be separated from the alcoholic extract by washing it several times with naphtha or petroleum ether. Phenols may be separated from naphthenic acids in the extract by saturating it with carbon dioxide, whereupon the phenols are liberated as a separate layer. Another method is to acidify the alcoholic caustic extract with excess strong acid such as hydrochloric or sulfuric acid, whereupon both phenols and naphthenic acids separate as an oil layer. On removing this layer and washing it with aqueous sodium carbonate solution, the

naphthenic acids are dissolved, leaving the phenols.

As sulfonating agents, strong sulfuric acid (of 90 to 95% concentration), fuming sulfuric acid, or liquid sulfur trioxide, may be used. Care should be taken not to use the stronger agents under such conditions as to affect the alkyl groups. For example, fuming acids are preferably avoided in sulfonating poly-alkyl phenols of which the alkyl groups are olefine polymers or contain long or highly branched carbon chains. Although sulfuric acid is preferred, it is possible to use other strong poly-basic mineral acids, such as phosphoric acid. Poly-alkyl phenol phosphates may also be prepared by reaction of the poly-alkyl phenol with phosphorous tri-chloride or with phosphorous oxy-chloride, followed by suitable hydrolysis to prepare the phosphoric acid derivative. Such phosphoric acids and their salts are used as detergent aids preferably in neutral or hard water, in which they are very effective.

Although the exact limitations of the various factors involved in the preparation of detergent aids according to the present invention are not known with absolute certainty, the following ranges and preferred conditions are believed to be sufficiently definite to guide those skilled in the art in carrying out this invention. The strength of the sulfuric acid to be used should be between 85% H_2SO_4 and 20% oleum (fuming acid), and the stronger the acid the lower should be the temperature at which it is used, although generally, satisfactory results are obtained by using the ordinary concentrated sulfuric acid (95% H_2SO_4) at a temperature between 70° F. and 160° F. With stronger acid, the temperature may be lowered to 32° F. or even 15 or -5° F., using inert diluent, such as a straight run or hydrogenated naphtha, if necessary. The conditions of the reactions should be preferably maintained so as to produce primarily mono-alkali metal sulfonates and preferably no disulfonates.

Proportions of the primary reactants, i. e., the alkyl phenols and the sulfuric acid, may be varied considerably, but ordinarily the ratio of sulfuric acid to phenol should be between the approximate limits of 3 to 1 and 1 to 1. The acid serves both as a reagent and a dehydrating agent, hence the stronger acids are used in smaller proportions. The time of contact will, of course, vary inversely with the temperature and concentration of acid, but ordinarily will be between the approximate limits of 10 minutes and 1 or 2 hours. Extremely short times of contact, e. g., substantially less than 1 minute, may be used with relatively concentrated sulfuric acid and at relatively elevated temperature.

Although sulfuric acid has been described above as the treating agent for effecting the combination of the olefine polymers with the phenols and also for attaching an inorganic radical which imparts good wetting properties to the compound, other strong poly-basic mineral acids, e. g., phosphoric acid, may be used instead of sulfuric acid.

The wetting agents prepared according to this invention may be used for a large variety of purposes, including among others: scouring agents, in conjunction with alkali, soap or both, dispersion of pigments and paints in water, in inks, in dye baths, in metal plating baths, in leather treating baths to improve the wetting of the leather, to improve the penetration of cos- 75

metics, the wetting of glue, with Portland cement to get better mixing, finishing pastes, for removing grease from steel, in lubricating oils, in lacquer emulsions, in paper manufacture to give the paper better absorption qualities, in combination with derris and pyrethrum for use in sprays, to get best coverage and toxic action, and may be used with lead arsenate in sprays, in oil and water emulsion sprays, and in miscible 10 oils for the preparation of emulsions.

This invention is not to be limited by any of the specific examples given, nor any theories advanced as to the mechanism of the operation of the invention, but only by the appended claims 15 in which it is intended to claim all novelty inherent in the invention as broadly as the prior art permits.

I claim:

1. Sodium poly-alkyl phenol sulfonate in 20 which the said alkyl groups each contain more than 4 carbon atoms.
2. Sodium di-amyl phenol sulfonate.
3. Improved detergent aid comprising, essentially an alkali metal salt of a strong poly-basic 25 mineral acid derivative of a poly-alkyl phenol in which at least two of the alkyl groups each contain more than 4 carbon atoms.
4. Improved detergent aid comprising essentially an alkali metal salt of a strong poly-basic 30 mineral acid derivative of a di-alkyl phenol in which the said alkyl groups are both branched and each contains from 5 to 8 carbon atoms.
5. Improved detergent aid comprising essentially an alkali metal salt of a strong poly-basic 35 mineral acid derivative of a di-tertiary alkyl phenol in which each of the alkyl groups contains from 5 to 6 carbon atoms.
6. Improved detergent aid comprising essen-

tially an alkali metal salt of a sulfonated di-amyl phenol.

7. Improved detergent aid comprising essentially an alkali metal salt of a sulfonated di-alkyl phenol in which the said alkyl groups each contain more than 4 carbon atoms, the said salt being substantially completely soluble in ether. 5

8. Improved detergent aid comprising essentially an alkali metal salt of a sulfonated di-amyl phenol, the said salt being substantially completely soluble in ether. 10

9. Process for preparing improved detergent aids comprising sulfonating a di-alkyl phenol having more than 4 carbon atoms in each of the alkyl groups. 15

10. Process for preparing improved detergent aids comprising sulfonating di-amyl phenol and neutralizing the resulting product with an alkali.

11. Process for preparing improved detergent aids comprising sulfonating di-amyl phenol, neutralizing the resulting product with an alkali, and separating from the neutralized reaction product the fraction soluble in ether. 20

12. An alkali-metal salt of a mono-sulfonic acid of di-tertiary-amyl phenol. 25

13. Poly-alkyl phenol sulfonic acid in which the said alkyl groups each contain more than 4 carbon atoms.

14. Di-amyl phenol sulfonic acid.

15. A strong poly-basic mineral acid derivative 30 of a poly-alkyl phenol in which at least two of the alkyl groups each contain more than 4 carbon atoms.

16. A sulfonic acid derivative of a di-alkyl phenol in which the said alkyl groups are both 35 branched and each contains from 5 to 8 carbon atoms.

LOUIS A. MIKESKA.
